METHOD OF COMBUSTION OF LIQUID FUEL

Edwin A. Jones and Michael L. Lavorgna, Milwaukee, and John C. Westmont and Sam C. Olson, Madison, Wis., assignors to L. J. Mueller Furnace Company, Milwaukee, Wis., a corporation of Wisconsin

Application May 11, 1938, Serial No. 207,184

2 Claims. (Cl. 158—117.5)

The present invention relates to improvements in oil burners and methods of securing complete combustion without pulsation and with a minimum of excess air.

One of the objects of the invention is to provide an improved method of securing complete and efficient combustion of fuel oil by means of an improved construction of oil burner for delivering the air relative to the atomized fuel for combustion.

Another object of the invention is to provide an improved oil burner combustion method by means of which air is fed to and across the flame at a rate which exceeds the speed of flame propagation adjacent the burner head so as to eliminate any fluttering, whistling or panting.

Still another object of the invention is to provide a method of securing combustion with an oil burner wherein the products of combustion have a high carbon-dioxide content with a high flame temperature resulting from a relatively small amount of excess air, whereby a high rate of heat transfer from the flame is assured together with maximum efficiency of the heating appliance in which the burner is installed.

Other objects and advantages of the invention will be apparent from the following description and the accompanying drawings in which similar characters of reference indicate similar parts throughout the several views.

Referring to the several sheets of drawings:

Fig. 1 is a vertical elevational view of an oil burner in partial section susceptible of performing the improved method;

Fig. 2 is an end elevational view of the burner head of Fig. 1, taken from the left of Fig. 1;

Fig. 3 is a fragmentary horizontal sectional view, taken on the line 3—3 of Fig. 1, looking in the direction of the arrows;

Fig. 4 is a vertical sectional view, taken on the plane of the line 4—4 of Fig. 1, looking in the direction of the arrows;

Fig. 5 is a vertical sectional view, taken on the plane of the line 5—5 of Fig. 1, looking in the direction of the arrows; and

Fig. 6 is a vertical sectional view, taken on the plane of the line 6—6 of Fig. 1, looking in the direction of the arrows.

Referring to Fig. 1, 10 indicates in its entirety an oil burner which comprises the usual controls, ignition and safety devices and is shown in connection with a blower housing 11 which rotatably supports on suitable bearings the impeller shaft 12 carrying a centrifugal fan rotor 13. Tangentially connected to the blower hous-

ing 11 is a discharge tube 14 which is provided with openings 15 and 16 at each end for the attachment of the additional parts of the burner.

The opening 15 is preferably closed by a cover plate 17 comprising a casting having an inwardly extending supporting lug 18 provided with a cylindrical bore 19 for receiving the fuel pipe 20. The fuel pipe may be secured in place by a set screw in the threaded bore 21. The cover plate 17 may be secured upon the opening 15 of the discharge tube 14 by a plurality of screws. An adjustment rod 26, having a slot 27 in its end, projects through an aperture 28 of the cover plate 17.

The air tube 14 is provided with a suitable attachment collar 29 for engagement with the attachment collar 30 of a supporting member 31 for the burner head, the two attachment collars being suitably secured together. The supporting member 31 is provided with an axially extending cylindrical flange 32 surrounding a relatively large cylindrical bore 33 which is adapted to receive an outer tube 34. The tube 34 is suitably secured in place within said bore.

At its outer or left end (Fig. 1) the outer air tube 34 supports an air supply head 36 which is provided with an outer cylindrical surface 37 adapted to be received in the outer tube 34. The head 36 is secured to the end of the tube.

The air supply head 36 comprises an annular metal member having an inner diverging frusto conical aperture 40 which surrounds the spray from the nozzle of the burner. The frusto conical surface 40 may be at an angle of approximately 10 degrees more or less to the axis of the collar 36 for the purpose of permitting the air to move outwardly with a spreading movement and to prevent the air from piling up at the flame discharge member 41 which is of conveying frusto-conical formation.

The air supply head 36 is provided with a plurality of rearwardly extending partially cylindrical flanges 42 located in spaced relation to the outer air tube 34 and separated from each other by a plurality of slots 43. An inner tube 45 is received at its forward end by the inner end of the supply head 36. The inner tube 45 may also be secured to a plurality of the cylindrical flanges 42 by screw bolts 46.

The cylindrical flanges 42 are provided with outwardly extending or tangential flanges 47 (see Fig. 4) each of which is located at one side of one of the slots 43, for the purpose of directing the air which is discharged from the slots 43 through the slots in a tangential direction. The

flanges 47 separate the space between the outer tube 34 and the cylindrical flanges 42 of the collar 36 into a plurality of compartments, each of which has a discharge aperture comprising a slot 43 extending into the frusto conical bore 40 in a tangential direction. The annular space 48 between the tubes 34 and 45 thus constitutes an air supply conduit which has its discharge points at the slots 43 for supplying air in a tangential and forward direction to the flame outside of the frusto-conical member 41.

The inner tube 45 fixedly supports the frusto-conical middle member 41 with its tapered flange 52, a circular discharge aperture 53, and a cylindrical attachment flange 54. The latter flange is secured to the tube 45 by suitable means (not shown).

The tube 45 supports at its right end a metal member 56 adapted to serve as a support for the nozzle pipe 20 and for the ignition electrodes 57, 58. The member 56 also acts as a partition and is provided with a gate 59 for controlling the supply of air to the inner tube 45. Member 56 has an outer substantially cylindrical flange 60 which is adapted to be received in the tube 45. It is also provided with an inwardly extending body flange 61 which supports an axially extending lug 62 having an axially extending bore 63 for receiving the fuel pipe 20.

30 Fuel pipe 20 is suitably secured in the bore 63. Thus, the member 56 is secured as a unit to the fuel pipe and to the cover plate 17 with which it may be removed and the cylindrical flange 60 slidably wedges within the tube 45. The insulated electrodes 57 and 58 are suitably held in position by boss portions of the flange 61. The fuel supply pipe 20 extends through the partition member 56 into proximity to the electrodes 57, 58, the threaded end of the fuel pipe 20 being 40 provided with a suitable fuel nozzle 81.

The partition member 56 is also provided with a segmental, axially extending flange 82 defining one side of an opening 83 which is adapted to be closed by the gate 59. The segmental flange 45 82 is provided with a pair of relatively straight edged portions (Fig. 3) 84—84 at each end and with an outwardly curved edge portion 85 between the straight portions. The flange 82 is thickened at 86 and the cylindrical flange 60 is 50 thickened at 87 to provide material for forming a bearing for the pin 88 which is located in the bore extending through these thickened portions. The head of the pin is located in a counterbore.

The gate 59 may comprise a member having a 55 flat body flange 91 which is slightly thickened at 92 to provide material for the bearing comprising the bore, by means of which the gate 59 is rotatably supported upon the pin 88. The shape of the gate 59 (Fig. 4) is such as to fill the aperture 83 so as to effect a substantial closure, although the gate is adapted to move freely in the aperture 83 under the influence of a spring 93.

Spring 93 has one end secured to a pin 94 which passes through the gate 59 and has its 65 other end secured to a lug 95 by means of a similar pin. Gate 59 has an upwardly extending projecting flange 96 which is adapted to engage the flat edge 84 (Fig. 3) of the flange 82. The gate is also provided at its free edge with a 70 cylindrical flange 97 extending from the upper edge of the gate and curving down around the periphery of the gate to a point adjacent the pivot 88.

The cylindrical flange 97 tapers in width from 75 the maximum width at the upper edge to zero

adjacent the lug or thickened portion 87. Thus, when the gate is slightly opened, the flange 97 is still adapted to close what would otherwise be a crack at the periphery of the gate, but permits an opening only at the upper edge of the gate 5 between the flange 96 and the edge 84. Thus, when air is discharged through the opening 83, it must be discharged upwardly and forwardly and take a spiral course within the tube 45. The opening of the gate disposes its body slightly in 10 a spiral direction and the aperture formed by opening of the gate discharges air in that direction. Air is then supplied through the inner tube 45 in a spiral and forward direction surrounding the spray and discharging through the aperture 15 53 of the frusto-conical member 41.

The amount of opening of the gate 59 may be regulated by a threaded adjustment rod 26 which is provided with pairs of lock nuts 99, 100, fixedly 20 secured upon the threaded portion 101 which is threaded into a threaded bore 102 formed in the lug 95. The inner end of the rod is rounded and bears against the gate 59 which may be opened by the pressure of the air or by the action of the rod 26. The nuts 99 and 100 define the maximum and minimum opening positions of gate 59 and should be so adjusted.

The operation of the oil burner is as follows:

The electrodes 57, 58 may be energized by any suitable form of continuous or intermittent ignition and are adapted to ignite the liquid fuel which is atomized and sprayed by the nozzle 81. Air for combustion is supplied to the spray by the inner tube 45, the air traveling within the tube in a spiral or rotary forward direction and discharging from the end of the member 45 which tends to restrict the flow of the air and therefore to accelerate the air at the nozzle opening 53. Additional air is introduced through the slots 43 in a tangential and forward direction and is discharged from the tapered opening 40 in such manner as to prevent the air from piling up at the frusto-conical member 41, the additional air being also introduced at a higher velocity so as to accelerate the flow of oxygen to the flame as 45 the flame projects outwardly while it is in combustion. The velocity of this air jet from the tapered opening 40 is greater than the velocity of that portion of the flame which breaks back toward its source, so that the flame is positioned 50 away from the firing head. The surface 40 of the head 36 is provided with spaced-apart apertures 105 through which air is also discharged to mingle with the air from the slots 43, and the air from these apertures is effective in facilitating 55 progressive combustion.

As has been mentioned heretofore, the present invention aims at the attainment of relatively perfect combustion with a minimum of excess air and with the provision of a stable flame which 60 is devoid of pulsation. In oil burning devices when the oil is sprayed into a hot chamber, vaporization first takes place, followed by oil cracking (either prior to or during combustion). During this process the more complex hydro-carbons 65 break down. This action is accompanied by a release of free carbon and free hydrogen and the formation of alcohols and aldehydes, which in general are unstable at elevated temperatures and are broken down by the action of heat into 70 carbon monoxide and free hydrogen.

It is a fact that luminosity of a flame is due to the incandescence of the free carbon particles, and if combustion is not complete, free carbon is released in the form of soot. It therefore 75

follows that free hydrogen is present and is burning in situations where this disassociation occurs. Hydrogen, in a free state, and the simpler hydrocarbons have excessive rates of flame propagation, particularly at high temperatures. Although apparently it has never before been fully explained, pulsation is caused by the flame striking back toward the nozzle and air discharge as the temperature increases, and this results in blocking the air supply as expansion occurs within the restricted area. This action is followed by momentary smothering and lowering of the temperature which causes the flame to recede, permitting a reestablishment of the air supply, followed by a continuous repetition of the first and then the second of these conditions, producing a pulsating fire.

There have been many attempts in the prior art to eliminate flame fluttering or panting, but such attempts have not been comparable to that of the present invention because the prior attempts, of which the U. S. patent to Vollmer No. 2,078,884 and British Patent No. 419,852 of 1934 are examples (and which exemplifications have not been based on a clear understanding of the cause and effect of flame fluttering), have attempted to overcome the difficulties by a recirculation of the products of combustion. In view of these disclosures, the reason for at least partial elimination of pulsation in the fire when recirculation was employed, is obvious, since the dilution of the oxygen in the air supply by products of combustion containing water and carbon dioxide, inert gases, which have replaced O₂, results in an air supply to the flame which contains less than the approximate 21% O₂ normally present, and which will tend to reduce flame velocity. This method is objectionable because it results in heating and fouling of the nozzle, electrodes, and other portions of the equipment. While initially this procedure may be effective, it ultimately becomes more and more difficult to obtain complete combustion as the inner portions of the equipment become more and more heated and fouled, and flame volumes will also be increased and flame temperatures will be reduced by this method. Furthermore the matter of adjustment becomes very critical.

The result in the present invention is a high efficiency conical flame from which panting, whiffing and fluttering is eliminated. Any number of vanes and slots may be employed, but they are preferably uniformly arranged around the periphery of the air supply head. In the present invention a highly desirable flattened, conical flame is produced, and the necessary air for supporting combustion is introduced uniformly and

progressively in such a manner that all of the air must come into contact with the burning oil and gases during combustion so that it is unnecessary to provide an excessive amount of air which will tend to reduce the temperature and efficiency in order to secure clean and complete combustion.

Our improved method of securing efficient combustion comprises the atomization by spraying of liquid fuel into air which mixture is ignited and the supply of air adjacent the spray with a forward motion, and the introduction of additional air at a higher velocity than the rate of flame propagation, at the root of the flame for the purpose of eliminating fluttering, whiffing or panting, and effecting smooth and uniform combustion. It will thus be observed that we have, by means of our improved method and construction of burner, solved the problem of eliminating fluttering, whiffing or panting of the flame with which we believe the entire oil industry is and has been for some time concerned. Also in the present invention there is in the products of combustion a higher percentage of CO₂ with a smaller amount of excess air than has been possible of attainment heretofore.

What is claimed as the invention is:

1. The method of combustion of liquid fuel, which comprises, delivering a jet of atomized liquid fuel along an axis toward a combustion zone, mixing the atomized fuel with primary air advancing along the axis with the jet at relatively low velocity and deflecting the outer portions of said primary air inwardly to produce a nebulous mixture proceeding slowly toward said zone, igniting the mixture, and thereafter injecting inwardly into the burning and axially advancing mass of mixture additional air moving at higher velocity and sufficient to support approximately complete combustion of the fuel. 40

2. The method of combustion of liquid fuel, which comprises, delivering a spreading jet of atomized liquid fuel along an axis and toward a combustion zone, simultaneously advancing an enveloping air supply along said axis at relatively low velocity and directing the air into the atomized fuel to produce a nebulous mixture proceeding slowly toward said zone, igniting the mixture, and thereafter injecting inwardly into the burning and axially advancing mass of mixture high velocity whirling additional air sufficient to support approximately complete combustion of the fuel. 50
